CLAIM

The ornamental design for full arch dental model base having a double row of apertures, as shown and described.

DESCRIPTION

FIG. 1 is a perspective view of the present invention.

FIG. 2 is a top plan view thereof.

FIG. 3 is a bottom plan view thereof.

FIG. 4 is a side elevation view thereof.

FIG. 5 is a front elevation view thereof; and,

FIG. 6 is a rear elevation view thereof.

1 Claim, 2 Drawing Sheets
